UNITED STATES PATENT OFFICE.

EDWIN L. HALL, OF DEAVERTOWN, OHIO.

HAY-CARRIER.

SPECIFICATION forming part of Letters Patent No. 340,913, dated April 27, 1886.

Application filed January 30, 1885. Serial No. 154,439. (No model.)

To all whom it may concern:

Be it known that I, EDWIN L. HALL, of Deavertown, in the county of Morgan and State of Ohio, have invented a new and useful Improvement in Hay-Carriers; and I do hereby declare that the following is a full, clear, and exact description of the same.

My invention relates to hay-carriers, and is an improvement upon that class of hay-carriers in which a frame moving upon trucks is provided with jaws adapted to operate in connection with a stem or projection on the hoisting-pulley, which engages with the jaws, and also releases the stop and catching mechanism.

15 My invention is shown as embodied in a two-way carrier, but parts of it are applicable to one-way carriers, and I do not limit myself in this respect.

The invention consists, first, of an improved gravity-catch; secondly, of an improved frame; thirdly, of a locking-bolt adapted to fall and hold the carrier in place; fourthly, of inclined edges of the upper opening of the neck of the carrier for lifting the gravity-catch; also, of devices for opening the catch.

20 It consists, further, in dividing the gravity-bolt and providing cut-away portions in the inclined edges, whereby the bolt is made to act as a stop and catch, and of various details, all 30 hereinafter set forth and claimed.

In the drawings, Figure 1 shows a side elevation of the carrier in place upon the track, and also the catch-bolt. Fig. 2 is a central longitudinal section through the carrier and catch-bolt, the carrier being shown in a locked position. Fig. 3 is a vertical section on line *x x* of Fig. 2, showing the bell-shaped clutch as spread by the track-iron. Fig. 4 is a perspective view of the neck, showing how it is 35 formed on its upper edge to suit the divided form of bolt. Figs. 5 and 6 are detail views of the catch-bolt. Fig. 7 shows a bottom view of the track-iron. Fig. 8 is a detail view of the clutch-jaws, showing them in position to 40 hold the load.

45 In these drawings, A is the track upon which the carrier moves, and B represents the main frame of the carrier, provided with trucks *b*, (one pair at each end,) fitted to bear upon the 50 track.

The main arms *a a* are preferably connected by bars *b'*, and this part of the frame is preferably cast in one piece. The lower part of

this frame of the carrier is provided with a cylindrical neck having a vertical opening or 55 chamber.

The bracket D is shown as composed of two pieces, *p p'*, which may be put on the neck and held by bolts *e f'* at the ends, and is supported on the neck by a rim, *g*, the bracket 60 being held loosely upon the neck and adapted to turn to any position required as the carrier runs one way or the other. One end of the bracket carries the main hoisting-wheel E, turning upon the bolt *e*. In the other end 65 is left a hole, *G*, for the end of the hoisting-rope. The bracket may be made, however, of one piece, in which case the enlarged rim *g* would be omitted, and the bracket would be supported on the neck in any convenient way. 70 Within this neck are pivoted the catching-jaws *ff*. They form, substantially, a bell-shaped mouth to receive the stem or extension of the hoisting-pulley. The division of this bell-shaped mouth is longitudinal of the 75 carrier, and the two parts are pivoted to swing laterally on the inside of the neck.

The inner or upper end of the bell-mouth is adapted on each side to receive and catch the head on the upper end of the stem of the hoisting-pulley. The two parts of the bell-shaped mouth are adapted to open below by gravity, so as to close the upper or catching end and normally assume this position. The stem in entering throws the upper ends of the bell 85 parts slightly outward, and they return by gravity and catch the stem. Each side of the gravity-catch has an upwardly-extended arm which projects above the opening in which the catch parts are pivoted, and these arms 90 are adapted to be spread by means hereinafter described. As the carrier approaches the catch-bolt and stop mechanism, and as the arms are spread, the supports of the bearings of the stem of the hoisting-pulley are separated and the hoisted pulley is allowed to drop. By this arrangement I avoid the use 95 of springs, and at the same time simplify the construction and make it more compact and less liable to get out of order.

100 My improved catch and stop mechanism is shown in Fig. 1 in section, the face of it being shown in Fig. 7. It consists of a plate, L, having a hollow shank, *l*, with an opening in the plate through to the face thereof, as shown 105 at *m*. In this shank is placed a bolt, M, hav-

ing an enlarged head to limit its upward movement, and adapted to project through the plate into the path of the carrier in line with the stem. The plate is set upon the under face 5 of the track, and the bolt fits loosely, so as to freely rise and fall. The edges of the upper part of the neck of the carrier-frame are inclined, as shown at $n\ n$, so that as the carrier approaches the catch-bolt the lower projecting end of it rides up the incline, and is thus lifted until it passes over the incline, when it drops and locks the carrier in position. The edges $n\ n$ are near enough to each other to locate the bolt when it drops directly over the catch 15 of the bell-mouth, so that when the stem of the hoisting-pulley rises it may lift the catch-bolt and release the carrier and allow it to move on the track. The whole action is thus automatic, the catch-bolt being lifted by the incline edge, dropping when the carrier has caused it to pass the edge to lock the carrier in place, while the stem of the hoisting-block lifts the bolt and releases the carrier at the instant when the stem is in position to be 25 caught by the gravity-catch.

The plate L is of the shape shown in Fig. 7. It is doubly wedged, extending equally in both directions from the catch-bolt, and directly in the path of the two arms $k\ k$. The 30 plate extends downward below the under surface of the track, so that as the carrier approaches the arms are spread by the wedge shape of the plate, whichever way the carrier be moved. When the central part of the carrier 35 reaches the central part of the plate, the arms are fully spread, and the stem of the hoisting-pulley is released.

I have thus far described the gravity-bolt as a catch, but I have also shown it constructed 40 to operate as a stop. For this purpose it is divided into two parts, $b^2\ b^2$, the division being longitudinal of the track. The parts are adapted to move independently, and are suitably limited in movement, so that they may 45 drop only the necessary distance.

The upper incline edge of the neck openings, heretofore referred to, which serves to lift the bolt, is cut away from side to center, as shown at 2 2, the cut-away portion 2 on one side 50 being opposite the high portion 3 on the other side. The cut-away portions are adapted to receive the one half of the bolt-head, and allow it to be passed up the edge of the neck. The other portion, not cut away, has the incline 55 n , and as the carrier approaches the catch-bolt one half of the bolt rides up the incline, goes over it, and drops within, serving as a catch, while the other half passes through the opening in the cut-away portion and strikes against 60 the high part of the opposite side, and thus serves as a stop, one part of the bolt thus serving to prevent the carrier from moving beyond the proper position and the other part preventing it from rebounding. The construction being symmetrical, it acts precisely 65 the same in either direction.

I do not limit myself as to this divided con-

struction of the gravity-bolt, but consider the gravity-bolt as the incline for lifting it, and in its relation to the carrier as new and of my 70 invention.

It will be understood that the gravity-bolt which holds the carrier, and the gravity-catch are equally applicable to a one-way carrier in which the bolt need not be divided, though 75 the opening into which it falls should be slightly elongated.

The frame and bracket may be adapted to a one-way carrier simply by fixing the bracket on the neck by a set-screw. 80

Having thus described my invention, what I claim as new is—

1. In a hay-carrier, a two-part bell shaped gravity-catch having its upper end adapted to receive and catch the stem of the hoisting-pulley, and having also upwardly-extending arms adapted to be spread by the plate on the under side of the track, substantially as described. 85

2. In a hay-carrier, a two-part bell-shaped gravity-catch pivoted in the lower hollow extension or neck of the carrier-frame, and having upwardly-extending arms adapted to be opened by a plate on the under side of the track, combined with a gravity-bolt, and with 90 the inclined edges at the upper opening of the carrier-neck, substantially as described.

3. In a hay-carrier, the combination, with the inclined edges at the upper opening of the carrier-neck, of a gravity-catch bolt adapted 95 to be lifted by the incline and to drop into the opening, substantially as described.

4. In combination, in a hay-carrier, a gravity-catch for the stem of the hoisting-pulley, located within an opening in the carrier-neck, and having upwardly-extending arms, the said opening having inclined upper edge, a gravity locking-bolt adapted to be lifted by the inclined edge of the opening, and a plate on the under side of the track adapted 105 to spread the arms of the gravity-catch and release the stem of the hoisting-pulley, substantially as described. 110

5. A locking-bolt set in the track and adapted to fall and project below the under surface 115 thereof, in combination with a carrier having a central chamber and suitable catch for the stem of the hoisting-pulley, said chamber being adapted to receive the locking-bolt, substantially as described. 120

6. In a hay-carrier, the combination, with a locking mechanism for the stem of the hoisting-pulley and the inclined edges at the upper opening of the carrier-neck, of the cut-down portions 2 2 and a divided locking-bolt, substantially as described. 125

In testimony whereof I have signed my name to this specification in the presence of two subscribing witnesses.

EDWIN L. HALL.
